(57) **CLAIM**

The ornamental design for a rowing machine as shown and described.

DESCRIPTION

FIG. 1 is a left-side elevational view of a rowing machine showing the new design;

FIG. 2 is a right-side elevational view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a first perspective view thereof;

FIG. 8 is a second perspective view thereof;

FIG. 9 is an enlarged view of portion '9' in FIG. 3; and, FIG. 10 is an enlarged view of portion '10' in FIG. 7 thereof. The broken lines shown in the drawings are for the purpose of illustrating portions of the article that form no part of the claimed design and for the purpose of illustrating the enlarged portions of the article and form no part of the claimed design.

1 Claim, 10 Drawing Sheets
